UNITED STATES PATENT OFFICE.

OSBORNE HEDLEY ABBOTT, OF LONDON, ENGLAND.

DRYING-CHAMBER.

1,302,490.

Specification of Letters Patent.

Patented May 6, 1919.

Application filed November 21, 1918. Serial No. 263,478.

To all whom it may concern:

Be it known that I, OSBORNE HEDLEY ABBOTT, a subject of the King of England, residing in London, England, have invented 5 certain new and useful Improvements in Drying-Chambers, of which the following is a specification.

This invention relates to drying-chambers of the type wherein a number of superposed 10 drying-compartments constituting cross-conduits are directly connected at one end to a vertical main air-supply conduit from which the current of hot air is deflected into the drying-compartments.

15 Heretofore a number of dampers adjustable at will at different points along this main conduit have been provided for deflecting the current of hot air forced through the apparatus by a fan. I have found that 20 it is impossible to obtain an equable temperature throughout the drying-chamber by adjusting the dampers by hand.

This invention has for its object to provide a drying-chamber of the type described 25 which shall automatically be kept at an equable temperature throughout.

A drying-chamber of the type described and according to this invention has a series 30 of baffles projecting approximately horizontally from the wall of the vertical air-supply conduit in line one with the floor of each drying-compartment, the said baffles being fixed and the distance between the edges of the baffles and the opposed edges 35 of the drying-compartment floors being graded so that a narrower space is provided as inlet for each successive compartment from the bottom upward. Preferably the drying-chamber is heated by heating-apparatus of a constant heat-delivering type (for 40 example a gas-burner).

Conveniently, the flue of the heating-apparatus is situated in the main or supply conduit and extends through the baffle-plates 45 therein.

A horizontal conduit may be provided at the bottom of the chamber, whereby atmospheric air enters the drying-chamber and the heating apparatus is arranged to directly 50 heat the bottom of the drying-chamber and thus the conduit. The horizontal air-admission conduit is conveniently situated above a horizontal flue for the gases of combustion, which flue preferably has baffles 55 therein.

Other features of the invention are described in detail hereinafter.

The invention is illustrated by way of example in the accompanying drawing 60

Figure 1 is a side elevation, partly in section, showing one form of drying-chamber constructed according to the invention, part of the casing being shown broken away and one of the trays and the partition next thereunder removed, and 65

Fig. 2 is a horizontal section taken on the line 2—2 of Fig. 1, one of the trays shown broken away.

Referring to the drawing, the drying-chamber A is supported by its bottom A¹ on the top plate B¹ of the furnace B for heating the air, the entire apparatus being carried by the frame C. The products of combustion arising from the gas-ring D or other heating-device in the furnace flow through a hole B² in the plate B¹ into the space between the bottom A¹ of the drying-chamber and the plate B¹. In this space are located baffles B³ which delay the flow 75 of the gases by making them take a tortuous course and thereby gives them a longer time in which to become sufficiently heated. 80

The drying-chamber is divided into a number of superimposed compartments by 85 means of slightly inclined partitions or bottoms E removably carried by angle irons E¹ mounted on the wall of the drying-chamber. Each compartment contains a tray F removably carried by angle irons F¹ mounted on the wall of the drying-chamber. One or more doors G are provided hinged on one side of the chamber, for enabling the trays to be inserted into and removed from the chamber. Each tray has a perforated bottom F² for enabling the hot air to rise 90 through it and through the material carried thereon. 95

The main hot-air supply conduit H in the drying-chamber is a space situated between 100 the rear ends of the partitions E and the back wall of the drying-chamber. Baffle-plates J carried by small brackets J¹ fixed to the wall of the drying-chamber are provided in this main supply conduit extending 105 nearly horizontally from the outside wall of the chamber toward the floors of the compartments into which the chamber is divided by the partitions E. The lower baffle-plates J do not extend forward as 110

far as the upper plates, so that the cross-sectional area of the main supply conduit gradually diminishes in the direction of flow of the hot air. Atmospheric air is 5 caused by the heat to enter the front of the apparatus through the opening K, travels along a zigzag course in the horizontal conduit K¹ located immediately above the bottom A¹ of the drying-chamber and the lower- 10 most floor, and then flows into the main supply conduit H. A grid-valve K² is provided at the opening K for regulating the rate of supply of air from the atmosphere to the main supply conduit. In this arrangement 15 the air is heated on entering the apparatus before flowing into the vertical main supply conduit.

In order to increase the temperature of the hot air in the main supply conduit the 20 smoke-flue L of the furnace mounted on the bottom A¹ is led through the main supply conduit H.

The main hot-air exhaust conduit M is situated inside the drying chamber of the 25 front wall thereof, although it will be understood that the exhaust conduit may be located at any desired place. In the construction illustrated the upper end of the exhaust conduit has a greater cross-sectional 30 area than the lower end, this being effected by placing the front supports E¹ and F¹ of the partitions and trays, respectively, at gradually increasing distances from the front wall of the drying-chamber. Owing 35 to the described arrangement of the baffle-plates J on the one hand, and the partitions E, the trays F and their supports on the other hand, the inlets for the upper compartments are made smaller in area than 40 those for the lower, and at the same time the outlets for the upper compartments are made larger in area than those for the lower.

The main exhaust conduit M terminates above the drying-chamber in a tube M¹, 45 into which the smoke-flue L of the furnace is led and continues concentrically therewith, for the purpose of increasing the rate of flow of air through the apparatus by accelerating the exhaust.

50 The partitions E and the bottoms of the trays F are arranged slanting upward in order to facilitate the flow of the hot air from the main supply conduit through the described compartments or cross-conduits to 55 the main exhaust conduit.

The operation of the described apparatus will be readily understood from the above. After the trays F carrying the material to be dried have been placed on their supports 60 in the drying-chamber and the door G has been shut, the air heated by the furnace B rises into the vertical main supply conduit H and flows thence in parallel through the compartments containing the trays into the 65 main exhaust conduit. Owing to the de-

scribed arrangement of the conduits and compartments the flow of the hot air in the latter is such that fresh hot air flows into each compartment and the drying action to which the material in each compartment is subjected is equal in all the compartments. 7

The insertion of a thermometer into such apparatus as usually effected results in a rush of cold air into the drying-chamber. To obviate this defect, an aperture A² is 75 made in the front wall of the drying-chamber at the exhaust conduit, and a cylindrical holder N is pivotally mounted at its ends on the wall of the chamber and arranged to rotate about its vertical axis in the said 80 aperture, one half of the holder being located inside the chamber and the other half outside. A thermometer O is mounted in the holder at one side thereof, so that when the holder is turned by its handle N¹ the thermometer can be readily removed from the 85 drying-chamber for inspection, or inserted therein, without cold air being able to pass into the chamber.

It is to be understood that various modifications may be made in the described apparatus without departing from the scope of the invention as defined in the appended claims. The arrangement must, however, always be such that the drying action of the 95 hot air in all the compartments is equal.

What I claim as my invention and desire to secure by Letters Patent is:—

1. In drying-apparatus the combination of, a drying-chamber, a number of superposed drying-compartments therein having spaced bottoms at one side of a vertical air-supply conduit common to them all and at the other side to a vertical exhaust-conduit common to them all, a series of baffles projecting approximately horizontally from the wall of the vertical air-supply conduit in line one with the bottom of each drying-compartment, the distance between the edges of the baffles and the one wall as well 100 as the opposed edges of the drying-compartment floors being graded so that a narrower space as inlet is provided for each successive compartment from the bottom one upward, and heating-means for heating 105 the air admitted to the air-supply conduit between the lower baffle and the lowest bottom.

2. In drying-apparatus the combination of, a drying-chamber, a number of superposed drying-compartments therein connected at one side to a vertical air-supply conduit common to them all and at the other side to a vertical exhaust-conduit common to them all, a series of baffles projecting approximately horizontally from the wall of the vertical air-supply conduit in line one with the floor of each drying-compartment, the said baffles being fixed and the distance 125 between the edges of the baffles and the op- 130

- posed edges of the drying-compartment floors being graded so that a narrower space is provided as inlet for each successive compartment from the bottom one upward, heating-means for heating the air admitted to the air-supply conduit, said heated air being delivered to the conduit between the edge of the lowermost floor and the edge of the lowermost baffle, and a flue for the gases of combustion from the heating-means which flue extends up through the vertical air-supply conduit and through the baffles therein.
3. In drying-apparatus the combination of, a drying-chamber, a number of superposed drying-compartments therein connected at one side to a vertical air-supply conduit common to them all and at the other side to a vertical exhaust-conduit common to them all, a series of baffles projecting approximately horizontally from the wall of the vertical air-supply conduit in line one with the floor of each drying-compartment, the said baffles being fixed and the distance between the edges of the baffles and the opposed edges of the drying-compartment floors being graded so that a narrower space is provided as inlet for each successive compartment from the bottom one upward, heating-means for heating the air admitted to the air-supply conduit, and a horizontal conduit at the bottom of the drying-chamber and above the heating-means which conduit communicates at one end with the atmosphere and at the other end with the vertical air-supply conduit in the drying-chamber.
4. In drying-apparatus the combination of, a drying-chamber, a number of superposed drying-compartments therein connected at one side to a vertical air-supply conduit common to them all and at the other side to a vertical exhaust-conduit common to them all, a series of baffles projecting approximately horizontally from the wall of the vertical air-supply conduit in line one with the floor of each drying-compartment, the said baffles being fixed and the distance between the edges of the baffles and the opposed edges of the drying-compartment floors being graded so that a narrower space is provided as inlet for each successive compartment from the bottom one upward, and heating-means of a constant heat-delivering type for heating the air admitted to the air-supply conduit.
5. In drying-apparatus the combination of, a drying-chamber, a number of superposed drying-compartments therein connected at one side to a vertical air-supply conduit common to them all and at the other side to a vertical exhaust-conduit common to them all, a series of baffles projecting approximately horizontally from the wall of the vertical air-supply conduit in line one with the floor of each drying-compartment, the said baffles being fixed and the distance between the edges of the baffles and the opposed edges of the drying-compartment floors being graded so that a narrower space is provided as inlet for each successive compartment from the bottom one upward, heating-means for heating the air admitted to the air-supply conduit, a horizontal conduit at the bottom of the drying-chamber and above the heating-means which conduit communicates at one end with the atmosphere and at the other end with the vertical air-supply conduit in the drying-chamber, a horizontal flue situated below the horizontal air-admission conduit but which second horizontal flue is connected at one end to the heating-apparatus and at the other end to the vertical flue for gases of combustion so that the gases of combustion pass from the heating-apparatus through this horizontal flue to the vertical flue and thereby heat the air entering by the horizontal air-conduit, and baffles situated in the horizontal flue to retard the passage of the gases of combustion therethrough.
6. In drying-apparatus the combination of, a drying-chamber, a number of superposed drying-compartments therein connected at one side to a vertical air-supply conduit common to them all and at the other side to a vertical exhaust-conduit common to them all, a series of baffles projecting approximately horizontally from the wall of the vertical air-supply conduit in line one with the floor of each drying-compartment, the said baffles being fixed and the distance between the edges of the baffles and the opposed edges of the drying-compartment floors being graded so that a narrower space is provided as inlet for each successive compartment from the bottom one upward, and heating-means of a constant heat-delivering type for heating the air admitted to the air-supply conduit.

In testimony whereof I affix my signature.
OSBORNE HEDLEY ABBOTT.
